United States Patent Office

Des. 197,538
Patented Feb. 18, 1964

197,538

JAR OR SIMILAR ARTICLE

William Dickison, Des Plaines, Ill., assignor to H. D. Hudson Manufacturing Company, Chicago, Ill., a corporation of Minnesota

Filed Sept. 27, 1961, Ser. No. 66,887

Term of patent 14 years

(Cl. D58—25)

FIG. 1 is a top plan view of a jar embodying my new design;

FIG. 2 is a side elevational view thereof;

FIG. 3 is a bottom plan view thereof; and

FIG. 4 is a horizontal cross-sectional view thereof taken on the line 4—4 of FIG. 2 and viewed in the direction of the arrows.

I claim:

The ornamental design for a jar or similar article substantially as shown.
